A. DE ROSE

MOP

Filed May 12, 1925

Inventor
ALBERT DE ROSE

By

Attorney

UNITED STATES PATENT OFFICE.

ALBERT DE ROSE, OF GILROY, CALIFORNIA.

MOP.

Application filed May 12, 1925. Serial No. 29,768.

The present invention relates to improvements in mops, and its principal object is to provide a mop that is very convenient in use and may be cleaned and flopped in a bucket of water and wrung for the purpose of drying the same without necessitating the touching of the wiping element by the operator.

A further object of the invention is to provide a mop having a detachable wiping element so that after the same is worn out, it may be easily replaced by a new one.

It is further proposed to provide a connection between the wiping element and the handle of a mop which engages the wiping element at both ends and allows the same to be arranged relative to the handle at any operative angle desired by merely placing the wiping element on the floor and depressing the lower end of the handle.

Further objects and advantages of my device will appear as the specification proceeds.

The preferred form of my invention is illustrated in the accompanying drawing, in which

Figure 1 shows a side view of my mop.

Figure 2 a sectional detail view taken along line 2—2 of Figure 1.

Figure 3 a side view of the lower end of the mop taken at right angles to that of Figure 1.

Figure 4 a similar view showing the wiping element twisted.

Figure 5 a view similar to that of Figure 3, showing the wiping element in angular relation relative to the handle.

Figure 6 a detail view showing a joint used in the supporting means for the wiping element.

Figure 7 a view of the same joint explaining the operation thereof, and

Figure 8 a side view of the lower end of the mop substantially similar to that of Figure 1 but showing the mop twisted.

While I have shown only the preferred form of the invention, I wish to have it understood that various changes or modifications may be made within the scope of the claims hereto attached without departing from the spirit of the invention.

The handle 1 of my mop is made of a hollow tube in which is mounted in suitable bearings 2 and with freedom of longitudinal sliding and of rotary motion a shaft 3 terminating at its lower end in a fork, the two prongs 4 of which spread in diametrically

opposite directions and are bent upon themselves to provide two arms 6 having their ends spaced as shown at 7 and allowing an endless wiping element 8 to be guided through the gap so as to be supported on the two arms. The wiping element 8 may be made of any suitable material and its far end is supported on a transverse member 9 of a frame 11 which is pivoted to the lower end of the handle as shown at 12 and has two extensions 13 projecting beyond the pivots. Two spring members 14 are arranged on opposite sides of the handle and have their upper ends fixed relative to the handle by means of collars 16 having ears 17 extending therefrom through which the said spring members pass. Somewhat lower on the handle a sleeve 18 is slidable on the handle and through ears 20 on the springs, its position being adapted to be fixed by means of a pin 19 passing through a hole in the sleeve into any one of a plurality of recesses 21 in the handle. This arrangement leaves the lower ends of the two springs 14 free for connection with the extensions 13 of the frame 11 as shown at 24. The lower ends of the springs yield when the wiper is placed on the floor and the handle depressed in the manner shown in Figure 5, so as to allow the wiping element to assume any desired angle relative to the handle. The tension of the springs 14 may be adjusted by raising or lowering the sleeve 18 on the handle, the spring becoming stiffer the lower the sleeve is arranged. The frame is preferably made with a joint 26 allowing the same to be opened for the introduction of the wiping element. I prefer to have the joint made as illustrated in Figures 6 and 7 in which one of the frame elements is shown as being cut along a zigzag line as at 27 so as to provide for toothed engagement of the adjacent ends with a sleeve 28 slidable on the frame element and adapted to be passed over the joint so as to hold the adjacent end pieces in place. The central shaft 3 extends clear through the handle and is provided at the top of the handle with a crank 31 by means of which the same may be revolved for the purpose of twisting and wringing the wiping element as illustrated particularly well in Figure 8. The upper end of the said shaft also has a cylindrical cap 32 fixed relative thereto which cap is made for engagement with the top end of the handle in the manner shown in Figure 1 with a spring 33 inter-

posed between the top of the handle and the top of the cap and tending to force the cap upwardly. This arrangement allows the cap upwardly and with it the shaft to be forced downwardly along the handle while the spring 5 automatically returns it to the normal position. This feature allows the operator to rapidly reciprocate the shaft relative to the handle whereby the wiping element is flopped back and forth for effecting a thorough soaking of the same when held inside 10 of a bucket full with water.

The manner of using my device will be readily understood from the foregoing description.

To soak the wiping element the same is dipped into a bucket of water and the shaft may be reciprocated rapidly for the purpose of effecting more thorough soaking and freeing 20 of the wiping element of dirt gathered therein during previous operations. If the mop is to be used wet, it may be lifted out of the bucket, placed on the floor and the lower end of the handle depressed which will allow 25 the wiping element to lie flat on the floor so that the latter may be cleaned by moving the wiping element back and forth over the floor. Where it is desired to use the wiping element as dry as possible, it may be conveniently wrung over the bucket by holding the handle and turning the shaft by means of the crank 30.

To remove the wiping element, the upper end thereof may be easily freed from the 35 forked end of the shaft by pushing the full width of the wiping element over on one of the arms 6 and then withdrawing the same through the gap 7 which leaves the wiping element suspended from the member 9 of the

frame. The sleeve 26 is then slid upwardly 40 on the frame element which allows the said element to be divided along the cut 27 so that the wiping element may be passed through the cut. The manner of inserting a new wiping element is obvious from the foregoing description. 45

I claim:

1. A mop of the character described comprising a tubular handle, a slidable and rotatable shaft extending through said handle, 50 a wiping element, means secured to the lower end of the shaft for supporting one end of the wiping element in proximity to the lower end of the handle, a frame pivoted to the handle and supporting the other end of the 55 wiping element, elastic means secured to the handle and engaging the upper end of the frame tending to maintain the frame in a plane passing through the axis of the handle, and a crank secured to the upper end of said shaft.

2. A mop of the character described comprising a tubular handle, a slidable and rotatable shaft extending through said handle, 65 a wiping element, means secured to the lower end of the shaft for supporting one end of the wiping element in proximity to the lower end of the handle, a frame pivoted to the handle and supporting the other end of the 70 wiping element, elastic means secured to the handle and engaging the upper end of the frame tending to maintain the frame in a plane passing through the axis of the handle, a crank secured to the upper end of said shaft, and a resilient element on the handle 75 tending to force the shaft upwardly therein.

ALBERT DE ROSE.
